UNITED STATES PATENT OFFICE.

CLYDE SLUSSER, OF CHARLESTON, WEST VIRGINIA.

BINDING-POST.

No. 818,480.

Specification of Letters Patent.

Patented April 24, 1906.

Application filed March 17, 1905. Serial No. 250,639.

To all whom it may concern:

Be it known that I, CLYDE SLUSSER, a citizen of the United States of America, and a resident of Charleston, Kanawha county, 5 West Virginia, have invented certain new and useful Improvements in Binding-Posts, of which the following is a specification.

The object of my invention is to construct a binding-post which when sold as an article 10 of manufacture may be readily adapted by the user to be secured to one of the parts to be connected in such one of a plurality of ways as is most convenient and to provide means whereby the wire or connecting-link 15 forming the other part to be connected may be readily, quickly, and securely caught with good electrical contact.

In order to provide the adaptability as to the manner in which the binding-post can be 20 secured, I use a hollow post, made of malleable or flexible material, preferably notched at its lower end, whereby one of the parts may be either caught within the diametrical notches and secured therein in any appropriate manner or by which the notched 25 lower end of the post may be bent either outwardly or inwardly in the form of a flange to permit the securing of the post to a flat surface or to hold it within a hole formed in the 30 part to which it is to be secured, for which purpose the outwardly-bent flange is especially applicable, while if the flange be bent inwardly a tubular binding-post will be formed having a restricted lower end with a 35 central aperture, through which aperture a bolt may be inserted, the head of the bolt resting within the tubular post and upon the inwardly-bent flange at the base thereof and the body of the bolt passing through the 40 part to which the post is to be secured.

For the purpose of providing means for securing the other part to the post I provide the post with an aperture, which may be either in the form of a perforation through 45 the post or in the form of a slot therein, and place around the post a coiled spring, the upper end of which bears upon a washer, also mounted upon the post and sliding thereon, the said spring tending to press the washer 50 upwardly and against the wire or conductor located within the aperture and to thus insure good electrical connection between the said wire and walls of the aperture, as I by preference make the washer itself of insu-

lating material in order that said washer 55 when the posts are used upon the electrode of batteries shall serve as spacing means to maintain the electrodes apart and prevent short-circuiting, a fault often present in the necessarily-compact batteries used in connection with the sparkers of explosive-engines driving automobiles.

My invention further consists in the construction, arrangement, and combination of the several parts of which it is composed, 60 which will be hereinafter more fully described and claimed.

Referring to the accompanying drawings, in which corresponding parts are designated by corresponding marks of reference, Figures 70 1 and 2 are side elevations of a binding-post constructed in accordance with this invention. Fig. 3 is a vertical section thereof, illustrating application of the same in the manner in which it may be applied to one of 75 the plates of a battery. Fig. 4 is a vertical section showing the binding-post as secured to a thin sheet of metal by formation of an outside flange and riveting. Fig. 5 is a detail illustrating the use of the binding-post 80 with an inside flange and a bolt or screw.

The post proper consists of a tubular piece 1, of malleable metal—preferably, for instance, of brass—the walls thereof being sufficiently thin to permit individual parts thereof to be 85 bent as may be desired, the body of the post having strength given thereto by its tubular form. By preference the metal at the bottom of the tube is notched axially or serrated, as shown at 2 in Figs. 1 and 2, thus permitting the user also to bend the several points of the post outwardly, forming an outside flange 2^a—as, for instance, shown in Fig. 4—or inwardly, forming an inside flange 2^b, as is shown in Fig. 5, or in case it is desired to 90 secure the post to the end of a thin plate, as one of the electrodes of the battery, the latter may be inserted in diametrical notches in the post and fastened therein by solder or in any other convenient manner, as shown in 100 Fig. 3.

While in Fig. 4 I have shown the outwardly-bent flanges as forming a riveted head caught beneath the part to which the post is to be secured, it will be obvious that such an outwardly-bent flange may be secured to the outer face of the plate by solder or in any other convenient manner, and it is shown as

riveted in the said figure merely to illustrate in detail one of the ways in which it is capable of use.

The upper end of the binding-post is spun ⁵ to form an outwardly-projecting flange 3 and to form a stop for the washer 5, encircling the body of the post, a spiral spring 6 also encircling the post below the washer, and when the post is secured to its supporting part the ¹⁰ spring bears on the upper surface of the latter and throws the washer toward the flanged head. Immediately below the flanged head the post is provided with a diametrical aperture 7, which in Fig. 1 is shown as a perforation, although it may be in the form of an ¹⁵ open slot, as indicated at 7^a in Fig. 3, to permit the insertion of a wire therein without threading its end through the perforation.

By the construction described the washer ²⁰ will be pressed against the under surface of the wire or conductor passed through the aperture and will also make direct electrical contact therewith itself or will force the conductor against the upper walls of the aperture, in either case affording good electrical ²⁵ connection.

In certain cases—for instance, when the posts are to be used on the electrodes of compact batteries—I prefer to make the washer ³⁰ of insulating material in order that they may serve as spacing-blocks to hold the battery-plates apart and prevent short-circuiting at their terminals. The change from an insulating to a conducting-washer, however, can ³⁵ be readily made by the user, as it will be seen that until the post is secured upon its base part the springs and washer thereon may be removed and replaced at pleasure to suit the demands of the occasion or the convenience ⁴⁰ of the operator. However, when the post

has been secured to its base, the parts will be held firmly in position without liability of loss.

Having thus described my invention, what I claim, and desire to secure by Letters Patent of the United States, is—

1. A binding - post for electrical circuits consisting of a hollow tubular part of malleable metal, a spring-contact maker mounted upon the exterior thereof and a support coöperated with the malleable end of the tubular part, substantially as described. ⁵⁰

2. A binding - post for electrical circuits consisting of a hollow tubular part of malleable metal, having a slot in the lower end, and a spring-contact maker mounted upon the exterior thereof. ⁵⁵

3. In a binding-post for electrical apparatus, the combination of a tubular part made of malleable metal, a spring encircling the ⁶⁰ said part and means upon the part for holding a conductor against the pressure from the spring and a support coöperated with the malleable end of the tubular part, substantially as described. ⁶⁵

4. In an electrical binding-post, the combination with a tubular part made of malleable metal and having a serrated lower end and a flanged upper end, of a spiral spring encircling the body of the said post, a washer interposed between the spring and flanged ends, and means upon the post for maintaining a conductor against pressure from the spring, substantially as described. ⁷⁰

Signed at Charleston this 15th day of ⁷⁵ March, 1905.

CLYDE SLUSSER.
